INVENTOR:—

James H. Lancaster

UNITED STATES PATENT OFFICE.

JAMES H. LANCASTER, OF NEW YORK, N. Y.

ACETYLENE-GAS GENERATOR.

SPECIFICATION forming part of Letters Patent No. 659,680, dated October 16, 1900.

Application filed October 9, 1899. Serial No. 732,984. (No model.)

To all whom it may concern:

Be it known that I, JAMES H. LANCASTER, a citizen of the United States, and a resident of New York, in the county of New York and State of New York, have invented certain new and useful Improvements in Acetylene-Gas Generators, of which the following is a specification.

My invention relates generally to portable lamps in which the illuminant used is generated in the lamp itself, and more particularly to lamps in which acetylene gas is the illuminant.

The object of my invention is to construct a safe, inexpensive, and efficient portable lamp; and to this end the invention consists, first, in a generating-compartment surrounded by a water tank or jacket, said tank having an inverse water-sealed fluid-inlet and a passage having a hand-regulated means for feeding the water from the jacket to the generating-compartment, the same passage serving to conduct gas from the generating-chamber to the water-compartment; second, in auxiliary means whereby the water-supply may be replenished without disturbing the operation of the lamp; third, in an improved gas and water tight cover embodying gas-purifying and gas-inlet means; fourth, in the general arrangement and combination of the different elements, all tending to produce a greater harmony of coöperation and regulation between said elements.

In the accompanying drawings I have shown my invention applied to a miner's lamp; but it will of course be understood that by so doing I do not confine myself to the exact construction shown, said construction only facilitating the explanation of my invention.

In said drawings, Figure 1 is a sectional view of a miner's lamp embodying my invention. Fig. 2 is a detail view of the grooved plug regulating the water-supply to the carbide. Fig. 3 is a modification of the water-inlet plug.

Similar letters of reference indicate corresponding parts in the different views.

I shall describe a miner's lamp adapted to the use of acetylene gas embodying my invention and afterward point out the novel features in the claims.

A indicates a shell forming the main body of the lamp provided with an internally screw-cut portion a' , into which the cover a^2 , supporting the upper ventilating portion B of the lamp, is screwed. The shell is further provided with a water tank or jacket C, surrounding said shell, in which the water used in the generation of the gas is stored.

The tank C is formed with two or more downwardly-projecting hollow bosses c' and c^2 , communicating with said tank, one of which, c' , is conically formed inside and has a passage c^3 leading into the shell A. Into this conical portion is fitted a corresponding plug c^4 , having an L-shaped passage c^5 and provided with a knob c^6 , so that communication between the water-tank C and the shell A may be had at the will of the operator simply by bringing the passage c^5 into alignment with the passage c^3 . A detension-spring c^7 is provided for retaining the knob in any desired position. The other boss c^2 has a tight-fitting threaded cover c^8 .

D is an inside shell provided with perforations d' and in which the carbide is contained.

E is a gas and water tight cover composed of a lower part e' , having a vertical guiding-flange e^2 and a horizontal annular flange e^3 , and having also a screw-cut hollow spindle e^4 and a screw-cut projection e^5 , serving as a continuation of the spindle. This projection, however, is not tubular throughout, but two or more passages e^6 branch off from this tubular portion at an angle to same, said passages being perforated throughout. It is further composed of an upper part e^7 , mounted on the spindle e^4 and provided with a conical flange e^8 , between which and the flange e^3 a rubber gasket or ring e^9 has been inserted. It further consists of a lowermost part e^{10} in the shape of a shallow dish having perforations e^{11} and having a central screw-cut bushing e^{15} fitting into the extension e^5 . In this shallow dish is placed suitable filtering material e^{16} for the gas to pass through. A thumb-screw e^{12} , tightening the parts together as they rest upon the shell D, is also provided, and an additional screw-cut extension e^{13} , carrying a suitable burner e^{14} , is attached to the uppermost part of the spindle e^4 , said hollow spindle communicating with said burner.

The superstructure of the lamp is of a well-known construction provided with a locking device b' and need not be described here.

In the use of my lamp the superstructure 5 B is first removed, then the gas and water tight cover E and the inside shell D. The shell A is now turned upside down and water introduced into the water-tank by removing the cap c^8 , care being taken that the passage 10 leading from the water-jacket to the shell A is closed. When the tank has been partially filled with water, the cap c^8 is replaced and the receptacle turned right side up, thus water sealing the passage through which the water 15 was introduced. The inside shell D is now inserted and partially filled with carbide and the tight-fitting cover E placed and tightened in position. Water is now introduced into the shell A by opening the plug e^4 , the water passing 20 from thence through the perforation d' into the shell D. The gas produced passes out into the shell A again and enters the lowermost part e^{10} through perforations e^{11} and passes through the filtering material up through the inclined 25 passage e^6 into the hollow spindle e and from thence to the burner e^{14} . The gas is then lighted and the superstructure B added and locked over the flame. Should the gas-pressure 30 in the carbide-holder become too great, the gas will seek a second outlet and will pass through the passage leading from the water-tank to the carbide-holder and bubble up through the water in the tank until the pressure in the two compartments is equal.

35 In Fig. 3 I have shown a modification of the plug c^8 . It simply consists in perforating the plug with a non-return fluid check-valve c^{15} , so that the water-supply may be replenished without disturbing the operation of 40 the lamp or the water seal, the fluid passing through said valve into the hollow boss c^2 , communicating with the water-tank. If for any reason difficulty should be experienced in feeding the water to the carbide, compressed 45 air may be introduced through this same valve c^{15} , likewise without disturbing the operation of the lamp.

From the above it will thus be seen that I have provided a safe, inexpensive, and efficient portable lamp requiring but little attention and admirably adapted to all uses where portable lights are utilized, and particularly to miners' lamps.

Having thus described my invention, what 55 I claim is—

1. In an acetylene-gas generator the combination of a main body forming the generating-chamber, a water-tank surrounding said main body and formed integrally with same, 60 a downwardly-projecting hollow extension

from said tank adjacent to the wall of the main body, a passage-way formed in the wall separating the main body and the extension of the water-tank, a rotatable plug inserted in said extension, a passage-way formed in 65 said plug for admitting water to the main body from the water-tank when in alignment with the passage-way of the wall of the main body, and a second downwardly-projecting extension from said water-tank provided with 70 a removable plug forming an inverse water-sealed inlet for said water-tank, substantially as described.

2. A removable cover, comprising three superposed parts, mounted on a common hollow 75 spindle closed at its lower end, substantially as described.

3. A removable cover comprising three superposed parts, a hollow spindle closed at its lower end formed integrally with the lower 80 part, annular flanges on the upper and lower parts and a rubber gasket introduced between said flanges, substantially as described.

4. In a removable cover comprising three superposed parts, a hollow spindle closed at 85 the bottom formed integrally with the lower part, a lowermost part containing filtering material, perforations in said lower part, and a plurality of passage-ways leading from said lower part to the tubular portion of the spindle, substantially as described.

5. In an acetylene-gas lamp a combined removable gas and water tight cover and filter, comprising three superposed parts, a hollow spindle closed at the bottom, and having a 95 screw-cut extension, formed integrally with the lower part, a lowermost part comprising a shallow dish with a screw-cut bushing fitting into the screw-cut extension of the spindle, and having a perforation, and a plurality 100 of passage-ways leading from the tubular portion of the spindle to the lowermost part, substantially as described.

6. In an acetylene-gas lamp comprising a main body, a water-tank surrounding said 105 main body and an inverted water-sealed water-inlet, inverted water-sealed fluid-introducing means adapted to be actuated without disturbing the operation of the lamp, substantially as described.

7. In an acetylene-gas lamp, a removable threaded plug, having a fluid-valve inserted, substantially as described.

Signed at New York, in the county of New York and State of New York.

JAMES H. LANCASTER.
